CHRISTIAN WM. MEINECKE, OF JERSEY CITY, NEW JERSEY.

DESIGN FOR A WATER-BAG.

SPECIFICATION forming part of Design No. 34,475, dated May 7, 1901.

Application filed March 19, 1901. Serial No. 51,941. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Water-Bag, of which the following is a specification.

My invention relates to a new and original design for water-bags, and is illustrated in the accompanying drawing, in which the figure is a perspective view.

The leading feature in my design resides in a water-bag having a width greater than its height, the bottom of the bag being substantially V-shaped and having a slightly-rounded apex, from which extends a perforated projection, said bag being provided at its top portion, at a point opposite the projection extending from the apex of its bottom, with a cylindrical neck, and with projections extending from its sides intermediate the neck and the projection extending from the bottom of the bag, the projections at the side and bottom sustaining a substantially triangular relation.

In the said drawing the reference-letter A indicates a water-bag the width of which is greater than its height, the bottom of the bag being substantially V-shaped, as shown at a, 30 and having a slightly-rounded apex, from which extends a perforated projection c, said bag being provided at its top portion, at a point opposite the projection c, with a cylindrical neck b, and with projections d extending from its sides intermediate the neck and the projection extending from the bottom of the bag, the projections at the side and bottom sustaining a substantially triangular relation. 35

My design presents a water-bag having a novel, pleasing, and distinguished appearance.

What I claim as new, and desire to secure by Letters Patent, is—

The design for a water-bag, substantially as herein shown and described.

In testimony whereof I have hereunto set my hand in the presence of two subscribing witnesses.

CHRISTIAN WM. MEINECKE.
